UNITED STATES PATENT OFFICE

DANIEL HERBERT SCHWEYER, OF EASTON, PENNSYLVANIA

AUTOMATIC TRAIN CONTROL

Application filed November 10, 1931. Serial No. 574,188.

My invention relates to improvements in automatic train control and has to do, more particularly, with train-carried receivers and the trackway means by which conditions are transmitted thereto.

Several serious problems have been found to exist in connection with inductive receivers in present use. Because rails are made of steel, trackway armatures must be spaced from the rails a considerable distance, and in order that a minimum amount of interference be had from crossovers and switches, it has been found preferable to dispose the trackway armature outside of, and parallel to the track. The most common systems of inductive train control now in use operate either upon the principle of inducing current in relay energizing coils carried by the train, or upon the principle of choking the winding upon an open core on the train by bridging the core gap with a trackway armature having an open-circuited winding. In order that such systems operate properly, extremely accurate adjustments, and highly sensitive electro-responsive control and indicating devices must be employed. In such systems the indicative current variations generated or suppressed are often extremely small and vary greatly in accordance with the speed of the train at the time of passage over the trackway element so that adjustments, at best, can be made only with average train speed as their basis. A train, thus equipped, moving over a trackway armature at extremely low speed, say five miles per hour, might pass into a danger block without receiving any indication whatever of such condition. And an automatic safety device which is not 100% operative under every possible condition is not only inefficient, but, because of the reliance naturally placed thereon, is a menace to safety and worse than no safety device at all.

With these and other factors in mind, my invention has for its purpose the accomplishment of several well defined objects.

The primary object of my invention is to provide a train control system which is more sensitive than systems heretofore in use.

Another object of my invention is to pro-

vide a train control system which will operate uniformly and accurately regardless of whether the train be traveling at high, moderate, or extremely low speed.

A further object of my invention is to provide a train-carried receiver which is simple in construction, positive in action, unlikely to require frequent adjustment, inexpensive to manufacture, and low in current consumption.

Further objects and objects relating to details and economies of construction and operation will definitely appear from the detailed description to follow. In one instance, I accomplish the objects of my invention by the devices and means set forth in the following specification. My invention is clearly defined and pointed out in the appended claims. Structures constituting preferred embodiments of my invention are illustrated in the accompanying drawing forming a part of this specification, in which:

Figure 1 is a diagrammatic representation of a preferred form of my invention as embodied in apparatus including a three-pole train-carried receiver core and a two-pole flux-shunting trackway armature;

Fig. 2 is a diagrammatic representation of an alternate form of trackway armature having three poles adapted for coaction with the three pole pieces of train-carried equipment such as shown in Fig. 1;

Fig. 3 is a diagrammatic representation of a modified form of my invention as embodied in a four-pole H type receiver core;

Fig. 4 is a diagrammatic representation of a modified form of my invention as adapted for operation with a single A. C. source, and showing a modified form of flux shunting trackway means; and

Fig. 5 is a diagrammatic representation of still another modification of my invention in which the receiver core is normally magnetized by D. C. and the control or indicating device is energized only upon the occurrence of a changed trackway condition as translated by the trackway armature.

In the drawing the same reference numerals refer to the same or similar parts throughout the several views.

Referring now to the numbered parts of my drawing, and more particularly to Fig. 1 thereof, there is diagrammatically illustrated a train-carried receiver comprising a three-legged yoke or core 10, on the outer legs 11 and 13 of which are disposed coils 14 and 15 which are so wound and connected to the A. C. source 16 as to jointly set up flux in the core 10. The middle leg 12 is at the flux center of the core and therefore is substantially free from flux set up by coils 14 and 15. An impulse coil 17 is disposed around leg 12 and a low power D. C. source 18 and a holding relay 19 are connected in series with coil 17. Associated with relay 19 and held closed so long as the relay circuit remains uninterrupted, is an indicator or control circuit comprising a relay controlled switch arm 20, a source of current 21, and a signal device or electro-energized brake control 22. A trackway-mounted element for influencing the train-carried receiver in accordance with trackway conditions comprises a core 23 having upstanding arms at its ends, a choke winding 24 intermediate its ends, and a relay or switch 25 for opening or closing the choke winding in accordance with trackway conditions. The circuits for operating relay 25 may be conventional and are therefore not illustrated.

The operation of the apparatus shown in Fig. 1 is as follows. Alternating current generated by the A. C. source 16 energizes coils 14 and 15, setting up a flux in core 10 as though it were of simple U form; that is, middle leg 12 is substantially free from A. C. flux. Impulse winding 17 on leg 12 therefore normally has no current induced therein and under such circumstances serves merely to complete the circuit connecting the weak D. C. source 18 to the relay 19 which maintains the switch 20 closed and the brake control or signal 22 energized by current source 21 in accordance with normal clear conditions. So long as the train and its core 10 do not pass over a trackway core 23 with an open circuited winding 24, the train-carried receiver will be unaffected. However, when the train-carried receiver passes over a trackway core 23 having a winding 24 which is not closed by the switch 25, that is to say, over a trackway armature actuated to indicate a caution or danger condition, strong A. C. flux is shunted through the trackway core 23 and the middle leg 12 superposing and neutralizing the weak flux set up in the leg 12 by the weak D. C. source 18, and by transformer action tending to set up an alternating current in impulse winding 17. However, superposition of one-half, or at most, a complete cycle of alternating current in winding 17 will provide a momentary cessation of current flow through the winding of relay 19 and allow relay arm 19a and switch arm 20 to drop, properly cutting off

source of current 21 from the indicator or control device 22 and providing a warning indication or the application of brakes.

In Fig. 2 there is shown a three-armed trackway element having two choke windings which may be used in place of the two-armed trackway element shown in Fig. 1. In this embodiment there is a three-armed core 26 having outer arms 27 and 29 and a middle arm 28. A pair of choke windings 30, 31, on the body of the core 26, are controllable singly, or in multiple, by the relay 32 which is, in turn, controlled by a conventional trackway block indicating circuit.

In Fig. 3 there is shown a somewhat modified form of train-carried receiver embodying my invention which comprises a core 33 of H form, upon the central bar 34 of which is wound a coil 35 which is energized by a comparatively strong D. C. source 36. One pair of opposed arms 37, 38, extend downwardly from the central bar 34 of the core and terminate in feet 37a and 38a, which are rather widely spaced from each other providing an air gap A and thus constituting, with central bar 34, a flux circuit of rather high reluctance. A second pair of arms 39, 40, branch from the ends of the middle bar 34 and terminate opposing each other across an air gap B of less width than gap A and constitute, with central bar 34, a flux circuit of lower reluctance than the aforementioned flux circuit including air gap A. Impulse coils 41, 42 are connected in series in a relay circuit which includes a holding relay 43 and a comparatively weak D. C. source 44. D. C. source 44 is so connected in the relay circuit that the flow of current, which would be momentarily induced in coils 41, 42 upon connection of D. C. source 36 to coil 35, would augment said D. C. source 44. Thus, and inversely, disconnection of the strong D. C. source 36 from coil 35 would result in a current kick momentarily overcoming the weak current made to flow in the relay circuit by weak D. C. source 44.

The operation of the apparatus shown in Fig. 3 is as follows. So long as the train and its receiver does not pass over the trackway element having an open winding, D. C. source 36 will energize coil 35, setting up flux in the flux circuit comprising central bar 34, arms 39 and 40 and air gap B. Little or no flux will be set up in the circuit including arms 37, 38 and air gap A, because of its greater reluctance. Once the D. C. source 36 has been connected to coil 35, no current will be induced in coils 41, 42, and the weak D. C. source 44 will maintain relay 43 stuck and the indicator or control circuit energized so long as clear trackway conditions continue to exist. However, upon the passage of the feet 37a, 38a of the receiver core 33 over a trackway core 23, having a choke winding 24 open-circuited by a relay 25, core flux set up

by coil 35 is immediately shunted through the circuit which includes legs 37, 38 and gap A bridged by core 23. The flux circuit including legs 39, 40, is thus instantly robbed and a current kick is set up in coils 41, 42, which is stronger than, opposed to, and overcomes the normal current flow effected by D. C. source 44. Relay 43 allows the arms 43a and 20 to fall, thereby appropriately indicating the danger condition or setting the train brakes.

In Fig. 4 there is shown a similar type of receiver adapted for energization and operation with a single A. C. source. As in the form shown in Fig. 3, there is an H type receiver core 33, having two pairs of opposed arms 37, 38 and 39, 40, the air gap A of which is wider than the air gap B. A coil 55 is disposed upon the central bar 34 of the core and is energized by an A. C. source 56, normally setting up an A. C. flux in the circuit defined by central bar 34, arms 39 and 40 and air gap B. Coils 51, 52 are wound on arms 39 and 40 and are connected in series to energize A. C. holding relay 53 with current induced in coils 51, 52. A somewhat modified trackway armature is shown in Fig. 4, which armature comprises a straight bar or core 123 having no legs and wound for substantially its entire extent with a choke winding or coil 124. The conventional relay 25 controls the opening and closing of the choke winding as in the other trackway elements shown. One advantage of the form of trackway armature shown in Fig. 4 is that there is a minimum of flux leakage around the winding 124.

The operation of the apparatus illustrated in Fig. 4 is as follows. A. C. source 56 constantly energizes coil 55, setting up flux in the central bar 34 of the core which flux normally passes through the flux circuit including arms 39, 40, and air gap B. Alternating current is thus induced in coils 51, 52 on arms 39, 40 and such current maintains holding relay 53 energized to hold relay arms 53a and 20 closed and thus properly control indicating or brake setting device 22. However, under danger conditions, relay 25 opens the choke winding 124 of the trackway armature causing core 123 to constitute a flux bridge for the air gap A. The flux circuit including arms 37, 38 and air gap A thereby becomes of lower reluctance than the circuit including arms 39, 40 and air gap B. Flux is thus shunted from the coils 51, 52, and little or no current is induced therein with the result that relay arms 53a and 20 fall and the danger indication is given, or the brakes are set, or both, depending upon the nature and construction of the element 22, which may take many forms.

In Fig. 5 there is shown a somewhat modified form of receiver embodying my invention and adapted for operation with a

single D. C. source. As in the form shown in Figs. 3 and 4, there is an H type receiver core 33 having two pairs of opposed arms 37, 38 and 39, 40, the air gap A of which is wider than the air gap B. A coil 65 is disposed upon the central bar 34 of the core and is energized by a D. C. source 64, magnetizing the core circuit of lower reluctance which includes arms 39, 40 and air gap B. Impulse coils 61, 62 disposed on arms 39 and 40 are connected in series to the magnetic relay 63 having a normally closed relay circuit arm 63a and a control or indicator circuit arm 120 which is closed in the absence of current flow in the relay circuit and maintains the indicator or control current source 21 connected to the indicator or control device 22.

The operation of the receiver shown in Fig. 5 is as follows. So long as the train does not pass over a trackway armature core 23 having a choke winding 24 which is open circuited, as by the relay 25, the arms 39, 40 will remain magnetized by D. C. flux set up by coil 65. Should, however, the train pass over an open circuited winding 24 and its core 23, the arms 39, 40 will be totally, or at least largely demagnetized by reason of a shunting of the flux into the circuit including arms 37, 38 and core 23. A current kick will thus be generated in coils 61, 62 and the electromagnet of the relay 63 will momentarily lift the arm 120, breaking off the current source 21 from the indicator or control device 22.

In equipment of the character above described, where the current which effects change in the electro-responsive indicating or control device is provided by induction in a secondary coil through which flux passes only when the receiver core is bridged by the trackway element, it is vital that such bridging exist for a space of time sufficient to cause a substantial current to be induced in the secondary coil. In the form of trackway element shown in Fig. 4, adequate bridging is assured even at exceptionally high train speeds and with a low frequency current source for the coil 55, due to the elongate form of the core 123. The same is true of the form of trackway element shown in Fig. 2. By way of illustration, should the receiver shown in Fig. 1 be used with a very low frequency current 16 and a very small trackway element of the form there shown, and should the train be traveling at a very high speed it might happen that the legs 11, 12 of the core 10 would completely pass over the core 23 during the moment when the sine wave of the alternating current flowing in coils 14 and 15 was at its crest. In that event the current induced in coil 17 would be negligible and insufficient to effect deenergization of the electro-responsive device 19. Using the form of trackway element shown in Fig. 2, it would be

impossible for the receiver core 10 to clear the core 26 during the moment the current wave was at its crest.

While I have disclosed what I regard to be preferred embodiments of my invention, such are illustrated primarily for the purpose of explaining the invention, and are by no means to be regarded as the only forms in which it is capable of embodiment. Numerous variations will appeal to those skilled in the art who become familiar with the concepts of the present invention. For example, while I have disclosed a choke-wound trackway element which effects bridging or shunting of a flux path of high reluctance by reason of open circuiting its winding, it is obvious that such bridging might be accomplished by an unwound bar of magnetic material and might be controlled by positioning the bar with respect to the line of the receiver core. While I have shown electromagnetic relay elements 25, 32 for operating the choke circuit switches, it is to be understood that other equivalent means, manual, or mechanical might be used. While I have found it preferable, in order to avoid interference by cross-overs and switches to so mount the trackway receiver core upon the train that it hangs some ten or twelve inches outside of the rail and cooperates with a trackway element disposed approximately two and one-half inches above the rail, under certain conditions, it might be desirable to dispose the receiver core and trackway armatures transversely of the trackway. Similarly, while I have varied the reluctance of the several flux circuits of the core by making air gaps therein of different widths, other methods such as using different core materials, different core cross section or auxiliary choking means might be substituted.

Further, while I have referred to the control current as alternating in character it is to be understood that this term is intended to include any suitable-fluctuating current and is not restricted to any specific frequency, since the apparatus will operate on frequencies lower than 60 cycles per second or higher even than 360 cycles per second. Likewise, while I have shown in Fig. 1, a pair of coils connected in parallel to the A. C. source, it is obvious that such coils, wound to differentially polarize the core, may be connected in series if desired. If desired, additional coils may be placed upon the legs 11 and 23 of the device shown in Fig. 1, so as to operate as a two-phase or three-phase system. Moreover, for the purpose of positively opening the relay in the secondary circuit of the form of apparatus shown in Fig. 1, Fig. 3 or Fig. 4, should the primary current source fail, a safety relay may be incorporated consisting of an electro-magnetic element in the primary circuit and a switch arm actuated thereby which controls continuity of the secondary

circuit. Numerous other variations within the scope of this invention will appeal to those skilled in the art.

It is to be understood that while the present invention is disclosed as embodied in a simple train control system indicating only clear or danger conditions, its concept is readily capable of embodiment in counting or translating train control systems and even in apparatus for performing other functions, for example, exploring systems for indicating the presence of hidden magnetic bodies. I, therefore, claim my invention broadly as indicated by the appended claims.

What I claim is:

1. In a train control system, a train-carried receiver including a magnetic core, a constant current source, winding on said core energized by said constant current source and setting up a normal flux distribution in said core, an electric-responsive control or indicating device, a second winding on said core, said second winding being so arranged with respect to the normal distribution of flux in said core and so electrically associated with said electro-responsive device that said device remains undisturbed during and only during the existence of said normal flux distribution in said core, and a trackway-mounted armature normally non-influential with respect to said receiver but rendered effective in accordance with adverse trackway conditions to shunt away a large portion of the flux normally existent in one portion of the core and thus effecting a current variation in the second winding which causes appropriate actuation of the electro-responsive control or indicating device.

2. In a train control system, a train-carried receiver comprising a three-legged yoke of magnetic material, a source of A. C., a coil on each of the outer legs of said yoke energized by said A. C. source, said coils being so wound with respect to each other that the middle leg of the yoke is normally neutral or free from flux set up by said coils, an impulse coil on said middle leg, an electro-responsive control or indicating device, and a source of current weakly energizing said device and impulse coil, said last mentioned current source being out of phase with said first mentioned A. C. source; and a trackway-mounted armature of magnetic material normally non-influential with respect to said receiver but rendered effective in accordance with adverse trackway conditions to magnetically bridge the space between the middle leg and an outer leg of the yoke thereby diverting yoke flux generated by the coil on that outer leg through said middle leg causing current to be induced in said impulse coil which is out of phase with and overcomes the current normally energizing said electro-responsive control or indicating device.

3. In a train control system, a train-carried receiver comprising a three-legged yoke of magnetic material, a source of A. C., a coil on each of the outer legs of said yoke energized by said A. C. source, said coils being so wound with respect to each other that the middle leg of the yoke is normally neutral or free from flux set up by said coils, an impulse coil on said middle leg, an electro-responsive control or indicating device, and a source of D. C. weakly energizing said device and impulse coil; and a trackway-mounted armature of magnetic material normally non-influential with respect to said receiver but rendered effective in accordance with adverse trackway conditions to magnetically bridge the space between the middle leg and an outer leg of the yoke thereby diverting yoke flux generated by the coil on that outer leg, through said middle leg inducing A. C. in said impulse coil which overcomes the D. C. normally energizing said electro-responsive control or indicating device.
4. In a train control system, a train-carried receiver comprising a three-legged yoke of magnetic material, a source of A. C., a coil on each of the outer legs of said yoke and connected in parallel to said A. C. source, said coils being so wound with respect to each other that the middle leg of the yoke is normally neutral or free from flux set up by said coils, an impulse coil on said middle leg, an electro-responsive control or indicating device, and a source of current weakly energizing said device and impulse coil, said last mentioned current source being out of phase with said first mentioned A. C. source; and a trackway-mounted armature of magnetic material normally non-influential with respect to said receiver but rendered effective in accordance with adverse trackway conditions to magnetically bridge the space between the middle leg and an outer leg of the yoke thereby diverting yoke flux generated by the coil on that outer leg through said middle leg causing current to be induced in said impulse coil which is out of phase with and overcomes the current normally energizing said electro-responsive control or indicating device.
5. In a train control system, a train-carried receiver comprising a three-legged yoke of magnetic material, a source of A. C., a coil on each of the outer legs of said yoke and connected in parallel to said A. C. source, said coils being so wound with respect to each other that the middle leg of the yoke is normally neutral or free from flux set up by said coils, an impulse coil on said middle leg, an electro-responsive control or indicating device, and a source of D. C. weakly energizing said device and impulse coil, said impulse coil, and D. C. source being connected in series; and a trackway-mounted armature of magnetic material normally non-influential with respect to said receiver but rendered effective in accordance with adverse trackway conditions to magnetically bridge the space between the middle leg and an outer leg of the yoke thereby diverting yoke flux generated by the coil on that outer leg through said middle leg inducing A. C. in said impulse coil which overcomes the D. C. normally energizing said electro-responsive control or indicating device.
6. In a train control system, a train-carried receiver comprising a three-legged yoke of magnetic material, a source of A. C., a coil on each of the outer legs of said yoke and connected in parallel to said A. C. source, said coils being so wound with respect to each other than the middle leg of the yoke is normally neutral or free from flux set up by said coils, an impulse coil on said middle leg, an electro-responsive control or indicating device, and a source of D. C. weakly energizing said device and impulse coil, said impulse coil, device, and D. C. source being connected in series; and a trackway condition transmitting element comprising a core of magnetic material of such length and so disposed with respect to the plane of the receiver yoke as to constitute a flux bridge diverting yoke flux generated by an outer leg coil through the middle leg of the yoke inducing A. C. in said impulse coil powerful enough to overcome the D. C. normally energizing said electro-responsive control or indicating device, and a choke winding on the core of said trackway element which when closed renders said core inoperative as a flux bridge for said yoke.
7. In a train control system, a train-carried receiver comprising a constant current source, a coil connected to said current source, a core of magnetic material having a trunk portion disposed through said coil and energized thereby and branches at the ends of said trunk portion which branches define two distinct circuits for the flux set up in said core, one of said circuits having less reluctance than the other circuit and normally constituting the preferred and main path for the flux, an electro-responsive control or indicating device, and an impulse coil wound around the normally preferred flux circuit, said last mentioned coil being so electrically associated with said electro-responsive device that said device remains undisturbed during and only during the presence of normal flux in said preferred circuit; and a trackway-mounted armature normally non-influential with respect to said receiver but rendered effective in accordance with adverse trackway conditions to so reduce the reluctance of the normally inoperative flux circuit as to cause flux to be shunted therethrough in preference to the normally preferred circuit thus effecting a current variation in the impulse

coil which causes appropriate actuation of the electro-responsive control or indicating device.

8. In a train control system, a train-carried receiver comprising a magnetic core of H-form, one pair of opposed arms of which are more widely spaced than the other pair, a coil on the middle bar of said core, a constant current source energizing said coil, an electro-responsive control or indicating device, and coils on the pair of opposed core arms which are less widely spaced, said arm coils being so electrically associated with said electro-responsive device that said device remains undisturbed while and only while the main stream of the core flux passes through core arms which are less widely spaced; and a trackway-mounted armature normally non-influential with respect to said receiver but rendered effective in accordance with adverse trackway conditions to constitute a flux bridge across the more widely spaced pair of opposed core arms, thus robbing the coils on the other pair of opposed arms of the flux normally existent therein.

9. In a train control system, a train-carried receiver comprising a magnetic core of H-form, one pair of opposed arms of which are more widely spaced than the other pair, a coil on the middle bar of said core, a constant current source connected to and energizing said coil, an electro-responsive control or indicating device, coils on the pair of core arms which are less widely spaced, and a source of D. C. weakly energizing said coils and electro-responsive device; and a trackway-mounted armature normally non-influential with respect to said receiver but rendered effective in accordance with adverse trackway conditions to constitute a flux bridge across the more widely spaced pair of opposed core arms, thus robbing the coils on the less widely spaced pair of opposed arms of the flux normally existent therein and causing a current kick in said coils which opposes the D. C. energizing the electro-responsive device.

10. In a train control system, a train-carried receiver comprising a magnetic core of H-form, one pair of opposed arms of which are more widely spaced than the other pair, a coil on the middle bar of said core, a main source of D. C. connected to said coil and polarizing said core, an electro-responsive control or indicating device, a second, and comparatively weak source of D. C., and coils on said less widely spaced pair of opposed core arms which are so connected in a series circuit with said device and said weak D. C. source that the flux set up in said less widely spaced arms by said main D. C. source is augmented by the flux therein set up by said weak D. C. source; and a trackway-mounted armature normally non-influential with respect to said receiver but rendered effective in accordance with adverse trackway condi-

tions to constitute a flux bridge across the more widely spaced pair of opposed core arms, thereby robbing the less widely spaced arms of flux and generating in the coils disposed thereon a current kick which opposes and overcomes the D. C. provided by said weak D. C. source of energizing said electro-responsive control or indicating device.

11. In a train control system, a train-carried receiver comprising a magnetic core of H-form, one pair of arms of which are more widely spaced than the other pair, a coil on the middle bar of said core, a source of A. C. connected to and energizing said coil, an A. C. holding relay governing a control of indicating circuit, relay energizing coils on said less widely spaced pair of opposed core arms in which current is normally generated by A. C. flux in said less widely spaced arms set up by the coil on said middle bar; and a trackway-mounted armature normally non-influential with respect to said receiver but rendered effective in accordance with adverse trackway conditions to constitute a flux bridge across the more widely spaced pair of opposed core arms, thus shunting and robbing the less widely spaced pair of core arms of the flux by which current is normally induced for energizing said A. C. holding relay.

12. In a train control system, a train-carried receiver comprising a magnetic core of H-form, one pair of opposed arms of which are more widely spaced than the other pair, a coil on the middle bar of said core, a source of D. C. connected to and strongly magnetizing said bar and the less widely spaced opposed core arms, a circuit opening relay, impulse coils on said less widely spaced core arms and connected to said relay; and a trackway-mounted armature normally non-influential with respect to said receiver but rendered effective in accordance with adverse trackway conditions to constitute a flux bridge across the more widely spaced pair of core arms, thus shunting the flux through the more widely spaced core arms and inducing a current kick in said impulse coils by reason of the drop in flux therethrough.

13. In a train control system, a train-carried receiver comprising a constant current source, a coil connected to said current source, a core of magnetic material having a trunk portion disposed through said coil and energized thereby and branches at the ends of said trunk portion which branches define two distinct circuits for the flux set up in said core, one of said circuits having less reluctance than the other circuit and normally constituting the preferred and main path for the flux, an electro-responsive control or indicating device, and an impulse coil wound around the normally preferred flux circuit, said last mentioned coil being so electrically associated with said electro-responsive device

that said device remains undisturbed during and only during the presence of normal flux in said preferred circuit; and a trackway-mounted armature normally non-influential with respect to said receiver but rendered effective in accordance with adverse trackway conditions to so reduce the reluctance of the normally inoperative flux circuit as to cause flux to be shunted therethrough in preference to the normally preferred circuit thus effecting a current variation in the impulse coil which causes appropriate actuation of the electro-responsive control or indicating device, said trackway armature comprising a magnetic core and a choke winding on said core which when closed renders said core ineffective as a flux shunt.

14. In a train control system, a train-carried receiver comprising a magnetic core of H-form, one pair of opposed arms of which are more widely spaced than the other pair, a coil on the middle bar of said core, a constant current source energizing said coil, an electro-responsive control or indicating device, and coils on the pair of opposed core arms which are less widely spaced, said arm coils being so electrically associated with said electro-responsive device that said device remains undisturbed while and only while the main stream of the core flux passes through core arms which are less widely spaced; and a trackway-mounted armature normally non-influential with respect to said receiver but rendered effective in accordance with adverse trackway conditions to constitute a flux bridge across the more widely spaced pair of opposed core arms, thereby robbing the less widely spaced arms of flux and generating in the coils disposed thereon a current kick which opposes and overcomes the D. C. provided by said weak D. C. source of energizing said electro-responsive control or indicating device, said trackway armature comprising a magnetic core and a choke winding on said core which when closed renders said core ineffective as a flux bridge.

15. In a train control system, a train-carried receiver comprising a magnetic core of H-form, one pair of opposed arms of which are more widely spaced than the other pair, a coil on the middle bar of said core, a constant current source connected to and energizing said coil, an electro-responsive control or indicating device, coils on the pair of core arms which are less widely spaced, and a source of D. C. weakly energizing said coils and electro-responsive device; and a trackway-mounted armature normally non-influential with respect to said receiver but rendered effective in accordance with adverse trackway conditions to constitute a flux bridge across the more widely spaced pair of opposed core arms, thus robbing the coils on the less widely spaced pair of opposed arms of the flux normally existent therein and causing a current kick in said coils which opposes the D. C. energizing the electro-responsive device, said trackway armature comprising

ing a magnetic core and a choke winding on said core which when closed renders said core ineffective as a flux bridge.

16. In a train control system, a train-carried receiver comprising a magnetic core of H-form, one pair of opposed arms of which are more widely spaced than the other pair, a coil on the middle bar of said core, a main source of D. C. connected to said coil and polarizing said core, an electro-responsive control or indicating device, a second, and comparatively weak source of D. C., and coils on said less widely spaced pair of opposed core arms which are so connected in a series circuit with said device and said weak D. C. source that the flux set up in said less widely spaced arms by said main D. C. source is augmented by the flux therein set up by said weak D. C. source; and a trackway-mounted armature normally non-influential with respect to said receiver but rendered effective in accordance with adverse trackway conditions to constitute a flux bridge across the more widely spaced pair of opposed core arms, thereby robbing the less widely spaced arms of flux and generating in the coils disposed thereon a current kick which opposes and overcomes the D. C. provided by said weak D. C. source of energizing said electro-responsive control or indicating device, said trackway armature comprising a magnetic core and a choke winding on said core which when closed renders said core ineffective as a flux bridge.

17. In a train control system, a train-carried receiver comprising a magnetic core of H-form, one pair of arms of which are more widely spaced than the other pair, a coil on the middle bar of said core, a source of A. C. connected to and energizing said coil, an A. C. holding relay governing a control of indicating circuit, relay energizing coils on said less widely spaced pair of opposed core arms in which current is normally generated by A. C. flux in said less widely spaced arms set up by the coil on said middle bar; and a trackway-mounted armature normally non-influential with respect to said receiver but rendered effective in accordance with adverse trackway conditions to constitute a flux bridge across the more widely spaced pair of opposed core arms, thus shunting and robbing the less widely spaced pair of core arms of the flux by which current is normally induced for energizing said A. C. holding relay, said trackway armature comprising a magnetic core and a choke winding on said core which when closed renders said core ineffective as a flux bridge.

18. In a train control system, a train-carried receiver comprising a magnetic core of H-form, one pair of opposed arms of which are more widely spaced than the other pair, a coil on the middle bar of said core, a source of D. C. connected to and strongly magnetiz-

ing said bar and the less widely spaced opposed core arms, a circuit opening relay, impulse coils on said less widely spaced core arms and connected to said relay; and a trackway-mounted armature normally non-influential with respect to said receiver but rendered effective in accordance with adverse trackway conditions to constitute a flux bridge across the more widely spaced pair of core arms, thus shunting the flux through the more widely spaced core arms and inducing a current kick in said impulse coils by reason of the drop in flux therethrough, said trackway armature comprising a magnetic core and a choke winding on said core which when closed renders said core ineffective as a flux bridge.
